UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPEWRITING MACHINE.

Application filed May 1, 1920. Serial No. 378,110.

To all whom it may concern:

Be it known that I, CORNELIUS B. CORCORAN, a citizen of the United States, residing in borough of the Bronx, in the county 5 of the Bronx, city and State of New York, have invented certain new and useful Improvements in Typewriting Machines, of which the following is a specification.

This invention relates to typewriting machines, and especially to the kind disclosed 10 in the patent to William A. Dobson, No. 1,335,956, dated April 6, 1920.

In such machines, the case-shift mechanism is preferably adapted to be locked in 15 the shifted position to enable the upper-case types to print. In small machines, certain difficulties arise since the mechanism is necessarily built of smaller and weaker parts, with the result that difficulties arise in making 20 the case-shift lock work satisfactorily. In the larger machines, a case-shift lock can be usually adapted to hold the case-shift mechanism at the limit of its throw, because the length of the key-lever allows the key-lever 25 to spring sufficiently to take up what lost motion is necessary to make the lock work satisfactorily. This springing of the key-lever allows the case-shift mechanism to be held at the limit of its movement even in 30 taking up lost motion of the lock.

The key-levers of the smaller machines, however, are so short that such locks as are used in the larger machines are unsatisfactory, because the lost motion cannot well be 35 taken up by the key-lever, with the result that, if the types are actuated when the case-shift lock is effective, the characters typed are out of alignment with the characters typed when the case-shift is held manually effective. Moreover, in smaller machines, if the desired portability is to be retained, the parts must be kept as light as 40 possible and yet have the requisite stiffness.

To obtain uniform alignment at the case-shift operation, whether locked or not, it has been found possible to provide a lock-arm for the case-shift key which, when swung to effective position, holds the case-shift mechanism substantially at the limit of its throw, the connections being such that the lock is held effective by mere friction, with the result that pressure upon the case-shift key is sufficient to allow the lock to be released.

In the invention as herein disclosed, the

locking-arm engages a lug which may be formed as part of the stamping out of which the case-shift lever is formed. The lug may spring from the case-shift key-lever near its front and extend backwardly 60 behind a comb or plate which carries the locking-arm at its back, thus enabling the lock to be easily adjusted, by bending the lug.

Where there is more than one case-shift 65 key-lever, each may be provided with a lug of this sort, and the lugs form easily adjustable members for obtaining the desired uniformity of action.

Other features and advantages will hereinafter appear.

In the accompanying drawings,

Figure 1 is a perspective view of a pair 75 of key-levers of the kind described, showing the present invention as applied thereto.

Figure 2 is a side view of the same, showing the parts in normal effective position.

Figure 3 is a view similar to Figure 2, showing the figure-shift key depressed and locked.

In the Underwood standard portable typewriting machine, the character keys 1 are adapted to print either in lower-case, capital-case or figure-case, by means of types, not shown herein. Normally they print in 85 lower case. When it is desired to print in figure-case, which is the highest case, the figure-shift key 2 is depressed, as in Figure 3, to carry its key-lever 3 around its pivot 4, so that the rear end 5 of the key-lever 90 lifts a rock-arm 6, which is adapted to lift the shift frame 7 from its normal Figure 2 position to the Figure 3 position. In doing this, the figure-shift key 2 causes a lug 8, near the rear end of its key-lever, to lift a 95 rock-arm 9 and rock to ineffective position a capital-shift stop 10, normally adapted to arrest the shift-frame when the capital-shift key is depressed. The rocking carries the stop 10 clear of the shift frame, and allows the shift-frame to rise until a lip 11 thereon strikes the figure-case-shift stop 12.

When in the Figure 3 position, the shift-key 2 is adapted to be locked by the pushing rearward of the finger-piece 13, formed as a 105 rock-arm having a lower extension or arm 14 which, at the actuation of the finger-piece, swings forwardly over a lug 15 on the key-lever. When the key-lever is in its Figure 3 position, the lower end 16 of the arm fric- 110

tionally engages the point 17 of the lug 15, and is held there by friction against the tension of the flat leaf spring 18, which is held by screws 19 to the back of the front 5 plate or comb 20, and tends to return the arm 14 and finger-piece 13 by pressing against a pin 21 upon the arm 14.

To enable the accurate adjustment of the lug with reference to arm 14, the lug is 10 formed as the rear end of a member 22, which may be integral with the key-lever 3 and may spring from the forward part thereof, as shown in the drawings, being bent over horizontally at 23, and comprising 15 a vertical rearwardly-extending body 24, which bends downwardly to its rear end where it engages the arm 14.

The arm 14 forms an integral part of the stamping which also includes the upper arm 20 25 terminating in the finger-piece 13, and which further comprises a bail 26 bent around and pivoted on the same shaft 27 that the arm 14 is pivoted on, and also bent downwardly to form a second locking-arm 25 28 for the capital-shift key 29. The shaft 27 is mounted in brackets 30 on the back of the plate or comb 20, and the finger-piece 13 extends through said plate. The arm 28 is adapted to lock the key 29 down, because 30 that key is on the front of a key-lever 31, having a lug forming the rear end of an extension 32, which may be like the extension 22 of the key-lever 3. Thus, when either key 2 or 29 is depressed, it may be locked 35 down by pressing rearwardly upon the finger-piece 13. Since the bottoms or lower ends of the arms 14 and 28 are nearly concentric with the shaft 27, the yielding of the key-lever, 3 or 31, under pressure of the 40 typist's fingers causes it to yield sufficiently to allow the spring 18 to make the locking-arm ineffective and thereby release the depressed key-lever.

Variations may be resorted to within the 45 scope of the invention, and portions of the improvements may be used without others.

Having thus described my invention, I claim:

1. In a typewriting machine, the combination with a case-shift mechanism and two case-shift key-levers, of a stop for the mechanism for each key-lever, an arm for each lever for holding it depressed, a rock-shaft to which both arms are fast, and an 50 integral extension of each of said key-levers connected at one end to the lever and having a lug at the other end, so that its lug can be adjusted up and down on the lever by bending the extension, so that its arm 55 can swing over and lock its lever when arrested by its stop.

2. In a typewriting machine, the combination with a case-shift mechanism and a case-shift key-lever, of a stop for the mechanism, a front plate beyond which the key-

lever projects, an arm behind the plate for holding the key-lever depressed, and an integral extension of said key-lever connected to the lever in front of the plate and having a lug at the other end behind the plate, 70 so that the lug can be adjusted up and down on the lever by bending the extension, so that the arm can swing over and lock the lever when the lever is arrested by the stop.

3. In a typewriting machine, the combination with a case-shift mechanism and two case-shift key-levers, of a stop for the mechanism for each key-lever, a front plate beyond which the key-levers project, an arm behind the plate for each key-lever 80 for holding it depressed, and an integral extension of each key-lever connected to its lever in front of the plate and having a lug at the other end behind the plate, 85 so that its lug can be adjusted up and down on the lever by bending the extension, so that its arm can swing over and lock its lever when arrested by its stop.

4. In a typewriting machine, the combination with a case-shift mechanism and two case-shift key-levers, of a stop for the mechanism for each key-lever, an arm for each lever for holding it depressed, a rock-shaft to which both arms are fast, an integral extension of each of said key-levers 95 connected at one end to the lever and having a lug at the other end, so that its lug can be adjusted up and down on the lever by bending the extension, so that its arm can swing over and lock its lever when arrested 100 by its stop, a spring normally holding the arms ineffective, and a finger-piece fast on said shaft for making the arms effective.

5. In a typewriting machine, the combination with a case-shift mechanism and a case-shift key-lever, of a stop for the mechanism, a front plate beyond which the key-lever projects, an arm behind the plate for holding the key-lever depressed, and an extension of said key-lever bent over to lie 105 alongside of it and to extend from in front of the plate to carry a lug behind the plate, so that the lug can be adjusted up and down on the lever by bending the extension, so that the arm can swing over and lock the lever when the lever is arrested by the stop.

6. In a typewriting machine, the combination with a case-shift mechanism and two case-shift key-levers, of a stop for the mechanism for each key-lever, a front plate beyond which the key-levers project, an arm behind the plate for each key-lever for holding it depressed, and an extension of each key-lever bent over to lie alongside of it 115 and to extend from in front of the plate to carry a lug behind the plate, so that the lug can be adjusted up and down on the lever by bending the extension, so that the arm can swing over and lock the lever when the lever is arrested by the stop.

7. In a typewriting machine, the combination with a case-shift mechanism and two case-shift key-levers, of a stop for the mechanism for each key-lever, an arm associated with each key-lever for holding it depressed, a shaft forming a pivot for the arms, a bail connecting the arms together to compel them to move in unison, and an extension of each of said key-levers rigidly connected at one end to the key-lever and having a lug at the other end, so that said lug can be adjusted up or down on the key-lever by bending said extension, so that the corresponding arm can swing into position to lock its associated key-lever when the key-lever is arrested by its stop.
8. In a typewriting machine, the combination with a case-shift mechanism and two case-shift key-levers, of a stop for the mechanism for each key-lever, an arm associated with each key-lever for holding it

depressed, a shaft forming a pivot for the arms, a bail formed in one piece with the arms and connecting the arms together to compel them to move in unison, an extension 25 of each of said key-levers rigidly connected at one end to the key-lever and having a lug at the other end, so that said lug can be adjusted up or down on the key-lever by bending said extension, so that the corresponding arm can swing into position to lock its associated key-lever when the key-lever is arrested by its stop, a spring normally holding the arms ineffective, and a finger-piece connected to the arms for overcoming the spring to make the arms effective. 30 35

CORNELIUS B. CORCORAN.
